UNITED STATES PATENT OFFICE.

EDMUND A. DEBUCHY, OF WEST HOBOKEN, NEW JERSEY.

AUXILIARY SIGHT FOR FIREARMS.

1,206,310.

Specification of Letters Patent.

Patented Nov. 28, 1916.

Application filed November 22, 1915. Serial No. 62,724.

To all whom it may concern:

Be it known that I, EDMUND ALFRED DEBUCHY, a citizen of the United States, and resident of the town of West Hoboken, county of Hudson, State of New Jersey, have invented certain new and useful Improvements in Auxiliary Sights for Firearms, of which the following is a specification.

10 The sight is the device by which firearms are aimed at the object at which they are intended to shoot and although there are many different kinds of sights employed, all sights may be generally included in two 15 broad classifications. The open sight which is used for general field or sporting purposes where extreme accuracy is not necessary but where rapidity is more to be desired. Such an open sight usually consists 20 of a member which may be a point or bead and which is secured to the outer end of a gun-barrel and a block having an upwardly projecting portion in which a V-shaped opening is cut, and which is usually secured 25 on the barrel, but at a point close to the firing mechanism or lock as it is sometimes called.

30 A closed sight usually consists of a bead as the outer member and a disk having a small perforation as the inner or near member of the sight. Such a sight is used for 35 very accurate work and it is usually adjustable as to elevation and sometimes transversely adjustable to compensate for wind pressures.

35 The fitting of the separate sights to a gun is a work that must be most carefully accomplished and therefore it is usually intrusted only to the manufacturer of the gun 40 so that it becomes a custom for the purchaser of a gun to predetermine the kind of sight with which the gun shall be equipped. It sometimes happens, however, that the owner 45 of a gun fitted with open sights will desire 50 to use the gun for more accurate work with the result that a new or different sight must be attached by one entirely familiar with the work of placing sights. This often occasions delay and inconvenience and it is to 55 obviate the necessity for this delay and most careful refitting that I have provided a device that may be readily attached to an ordinary open sight and which when so attached will provide all of the advantages of the so called peep-sight.

My invention relates to such an attach-

ment and from the description which follows, it will appear that when properly constructed, a closed sight may be placed in position by the owner or operator of the 60 gun with an assurance of the same accuracy that would result were a more complicated closed sight attached by an expert.

The following is what I consider a good means of carrying out this invention, and 65 the accompanying drawing forms a part of the specification, in which—

Figure 1 shows a rifle with my sight attached. Fig. 2 a perspective view of the sight. Fig. 2^a a clamping means which 70 holds the sight in position. Fig. 3 an elevation of the sight in operable position. Fig. 4 a sight of a modified form. Fig. 5 a sight of a further modified form and having a different attaching means, and Fig. 75 6 a side elevation of the sight shown in Fig. 5.

Similar reference numerals indicate like parts in all the figures where they appear.

In referring to the drawings, it will be 80 noted that I have shown what I will refer to as a rifle. In presenting the rifle no attempt is made to set forth a gun of any particular construction, shape or design, as I 85 desire it understood that my device may be employed with rifles, guns, or revolvers of almost any type. I will therefore indicate the entire rifle at 1, referring by that character to any firearm equipped with an outer sight 2 and an inner sight. The inner sight 90 here shown is a metallic member having a body portion 3 adapted to be attached to the gun and an upwardly extending portion 4, projecting upward from the surface of the gun. In the sight shown the outwardly projecting member is curved and by means of a 95 screw 5 and the slight flexibility of the body portion of the sight, the upwardly extending part is brought to a proper elevation.

In the upwardly extending portion of the 100 sight is a V shaped aperture 6^a shown in dotted lines in Fig. 3. This together with the part 2 provides the means by which the gun is usually aimed.

To produce a closed or peep-sight, I 105 provide a member shown in 2 and 2^a which consists of a forward plate 7 having a centrally disposed counter-sunk aperture 8 and a plurality of inwardly projecting recesses 9 and 10.

110 Formed integral with the plate 7 is a back plate 11 having a perforation in direct

line with the perforation 8 and a plurality of recesses 12 in its sides in line with the recesses 9 and 10. The space 13 between the plates 7 and 11 is sufficient to receive the upwardly extending portion 6 of the inner side and when the device shown in Fig. 2 is slidably engaged upon the portion 6 of the open sight, I secure it thereto by means of a clamp.

- 10 The clamp referred to should be formed of hardened steel and is provided with inwardly projecting tongues 15 and 16 adapted to pass into the recesses 9, 10 and 12 and to engage upon the portion 6 of the open sight. The forward end of these tongues 15 and 16 may be sharpened as shown in Fig. 3 so that a more firm engagement will result. To prevent my device from moving upward, I provide two downward extensions 17 and 18 formed integral with the tongues 15 and 16 and I connect these extensions together by means of a bar 19 which will pass under and engage with the curved portion 4 of the open sight. It will be noted that in placing my device, the perforation 8 is so arranged that it will assume a position directly in line with the lowermost portion or apex of the V, 6^a and therefore insure the proper alignment of my auxiliary sight.
- 20 When an open sight is again desired, the clamp may be readily removed and my closed sight drawn upward out of engagement with the open sight of the rifle and it will appear obvious that my device may be attached or removed at will by the operator and without delay and that it may be carried in the pocket ready for instant attachment.

I have found that a closed sight having a greater area than the one thus far described may be preferred from the fact that in using closed sights, it is desirable to exclude cross or confusing lights. I may therefore round the top of my sight in the manner indicated at 20 in Fig. 4, or I may make the back plate circular as shown at 21 in Fig. 5 slightly

increasing the diameter of the counter-sunk portion indicated at 22 in this figure so as to obtain all of the advantages of a large sight sometimes called a wind-sight. I may also provide other and simpler means for attaching my auxiliary sight, such a means as shown in Figs. 5 and 6 where the bottom portion of the front plate is inturned as shown at 23. This sight may be of flexible 55 steel or other suitable material and may be attached by being snapped over the open sight or being removed inwardly from a side of the member 6.

Other modification in size, shape or design, may be made to meet different conditions and changes not here referred to, within the scope of the appended claims without departing from the principle or sacrificing the advantages of the invention.

Having carefully and fully described my invention, what I claim and desire to secure by Letters Patent is

1. A rifle having an ordinary notched sight and an auxiliary sight comprising a perforated plate and a frictional clamp adapted to secure it in position with the perforation coinciding with the notch of said sight.
2. The combination with a notched sight for firearms of a perforated front and back plate formed integral and adapted to engage upon said sight and coöperate therewith as and for the purpose set forth.
3. The combination with a notched sight for firearms of a perforated front and back plate formed integral and adapted to engage upon said sight with said perforation coinciding with the notch thereof and a clamp adapted to secure said device in operable position upon said sight.

Signed at New York, city, county and State of New York, this 13th day of Nov. 1915, in the presence of two witnesses.

E. A. DEBUCHY.
